CLAIM

The ornamental design for a doll house, substantially as shown and described.

DESCRIPTION

FIG. 1 is a top plan view of a doll house showing my new design;

FIG. 2 is a side elevational view thereof;

FIG. 3 is a front elevational view thereof, and,

FIG. 4 is a rear elevational view thereof.

The surface textures partially indicated on the wall, roof and chimney members represent an overall pattern on those surfaces.

FIG. 1

FIG. 3
